UNITED STATES PATENT OFFICE.

ANDREW M. ERNSBERGER, OF NEW YORK, N. Y., ASSIGNOR OF ONE-HALF
TO ARTEMAS WARD, OF SAME PLACE.

AMALGAMATOR.

SPECIFICATION forming part of Letters Patent No. 650,581, dated May 29, 1900.

Application filed May 7, 1897. Renewed October 31, 1899. Serial No. 735,424. (No model.)

To all whom it may concern:

Be it known that I, ANDREW M. ERNSBERGER, a citizen of the United States, residing at New York, in the county of New York and State of New York, have invented certain new and useful Improvements in Amalgamators; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention is more especially designed to recover the fine gold from metal-bearing sands and tailings from stamp-mills which have usually proved too elusive for other methods in use, being particularly adapted for use in what are popularly described as "dry placers." The means which I employ for such purpose are illustrated in the accompanying drawings, where like parts are designated by similar reference-figures in every view.

Figure 1 is a side elevation, Fig. 2 is a plan, Fig. 3 is an end elevation, and Fig. 4 is a half-plan, of the disintegrating-cylinder. Fig. 5 is an elevation in cross-section of the disintegrating-cylinder on line A B, Fig. 1. Fig. 6 is a plan of disintegrating-rod clamps. Fig. 7 is an elevation of the same. Fig. 8 is an elevation of disintegrating-shaft, showing its step and step-holder in section. Fig. 9 is an elevation of one end of the distributors with one holder. Fig. 10 is an end view of the same. Fig. 11 is a central vertical longitudinal section.

My machine has a general framework formed by cross-subsills 1, upon which the structure is supported upon the ground and upon which longitudinal sills 2 are placed at each side. Attached thereto and rising therefrom are posts 3 4 5 6 7 upon each side of the machine and carrying longitudinal string-pieces 8 9 upon each side, the two side frames thus constructed being connected and held to each other by suitable cross-sills, and the side frames have braces 21 22. However, this exact construction need not be closely followed, as some of its members might be omit-

ted or differently disposed, it only being essential to substantially support my mechanism upon a suitable framework, which is shown made of wood, such being deemed suitable and preferable as saving expense in transporting the framework, if of metal, from points remote from its place of erection and use. 55

Supported near one end of the framework is a drum 23 upon a shaft 24, revolving in bearings 25, formed to be movably seated upon supports 26, secured to the framework at each end of the drum 23. Adjusting-screws 27 are attached to the bearings 25 and are thereafter fixedly secured to the framework 65 at their opposite end by brackets 28, collars 29 being upon the screws inside of the brackets 28 and hand-wheels 30 being upon the screws 27 outside of the brackets 28, thus fixing the screws in stationary position on the 70 frame, so that by turning the hand-wheel the screw moves the bearing, its shaft, and the drum toward or from the bracket, according to which way the screw is turned to the right or left. The drum 23, it will be seen, extends 75 across the machine, but within the framework. At the opposite end of the framework from drum 23 I place another drum 31, of the same dimensions as drum 23, mounted upon a shaft 32, secured in boxes 34, seated upon 80 the framework in fixed position. Upon these drums 23 31 I place an amalgamated belt 33, of copper or other suitable material, its top running in the direction from 31 to 23, as shown by the arrow in Fig. 1. Upon the outer 85 side of belt 33 at each edge I attach thereto dams 35, preferably made of rubber. Upon one end of shaft 32 I place a pulley 36, and outside of which I place another pulley 37, which is run from the source of power and 90 drives all of my mechanism.

Mounted upon string-pieces 9 and secured thereto above shaft 32, but beyond its vertical line, are supports 38, to which is secured a cross-piece 39, preferably a T-iron, on which 95 rests a vertical disintegrating-cylinder 40, having a cover 41 over its top. Within the disintegrating-cylinder 40, near its lower inner side, I secure a segmental ring 42, having recessed pockets 43 at its upper and outer side, 100 there being preferably four pockets in each segment. At the junction of the segments

there are formed other recessed pockets 44, one-half of each pocket being in each adjoining segment. Within the reduction-cylinder at its upper end is secured another segmental ring 45, having preferably four vertical slots 46 therethrough in each segment at its outer side and at the junction of the segments other vertical slots 47, they being formed with one-half in each adjoining segment. Bars 48 of rectangular section are placed into each slot 46 and, passing downward, enter and are seated and rest in the pockets 43 in segmental ring 42 and preferably coming flush with the top of segmental ring 45 and disintegrating-cylinder 40. Within slots 47 and seated in pockets 44 are breaker-bars 49, reaching from pockets 44 to the top of slots 47 and having thereon upon the inner side projecting fingers 50, reaching inwardly toward the center 20 of the disintegrating-cylinder 40 and spaced somewhat apart along the bars 49. The disintegrating-cylinder 40 will be secured in vertical position by supports 51, secured to the framework.

25 Mounted upon the cross-piece 39 at the center of the lower end of disintegrating-cylinder 40 is a step-bearing 52, within which is seated a step 53, in which rests the lower end of a vertical shaft 54. Above the step 53 on 30 the shaft 54 is secured a collar 55, on which rests a pair of washer-clamps 56, having right-angled grooves 57 within their adjoining sides, wherein are placed rods 58, extending outwardly at right angles to each other and 35 nearly approaching bars 48 49. Within the cylinder 40 the washer-clamps 56 are provided with a central hole 59 to fit over the part of the shaft 54 from above collar 55 to clamp-nut 60, which is at this part of rectangular 40 section, to prevent clamp-washers 56 from turning on the shaft. There are several pairs of washer-clamps 56 and rods 58 on the shaft 54, spaced apart by thimbles 61, surrounding the shaft 54 and of the proper length to cause 45 rods 58 to pass about midway between fingers 50 of bars 49, all being tightly clamped to position by nut 60. Above nut 60 a bearing 62 is secured, as seen in Fig. 3, to frame member 63 and in which the shaft 54 is guided and 50 run. Above bearing 62 a pulley 64 is secured to shaft 54, and thereon is run a quarter-turn belt 65, which passes outward over pulleys 66 67, held by brackets 68 69, secured to frame-piece 70, and thereafter belt 65 passes downward and over pulley 66, secured to shaft 32. A shield 71 is attached to shaft 54 and extends down outside of the upper part of step-bearing 52 to exclude any substance from coming in contact therewith and prevent any lubricating material from being thrown off.

55 At the lower end of disintegrating-cylinder 46 are secured two nearly-semicircular downwardly-inclined chutes 72, lead-lined and having multiple tapering directing-ribs 73 thereon to guide and equally distribute material from within cylinder 40 to belt 33, a space 74 being left between the chutes 72 for the de-

livery of the material, which space extends across the entire width of belt 33 and between dams 35.

Above disintegrating-cylinder 40 a hopper 75 is secured to parts 76 77 at either side of the framework. Within the hopper 75, across it near its bottom, I place right and left hand screws 78 79 on a shaft 80, carried in bearings 81, one end of the shaft extending outward from the hopper and having thereon a sprocket-wheel 82 beyond the framework. The screws 78 79 when turned force outward the material placed or fed into the hopper 80 each way to the spouts 83 84, which are attached and open into the bottom of the hopper 75 and thereafter extend downward through the cover 41 and into the disintegrating-cylinder 40, where they deliver the material forced into them. Above the screws 78 79 are slides 85 86, which extend through the outer sides of the hopper 75 to enable them to be moved to increase or decrease the space 87 between them, and thus regulate the amount of material fed to the screws 78 79. Above the slides 85 86 are inclines 88 89, sloping toward the space 87 to facilitate the flow of material by its own gravity. The wheel 82 is revolved by a sprocket-chain 90, 95 also running over a sprocket-wheel 91, secured on shaft 32. Drum 23 and belt 33 are positively moved and in unison by sprocket-wheels 92 on shaft 32 and 93 on shaft 24, connected by sprocket-chain 94. Near drum 100 33, somewhat below its center, I secure a water-tank 95 to the framework and partially immerse a revolving brush 96 therein, this brush being composed of multiple sections placed upon a shaft 97 and carried by arms 105 98 at each end, they being secured upon a pivotal shaft 99, secured to the framework at a point vertically back of the center of brush 96. The arms 98 extend outward beyond the framework and are provided with handles 100 and having slots 101, through which and into the framework clamping-screws 102 are inserted, so that by forcing down the handles 100 the brush 96 will be carried against the belt 33 as it runs over the drum 110 31. The brush 96, as shown, runs in water in tank 95 and projects a quantity of the water against the belt 33 to wash it, the shaft 97 being driven by pulley 103 upon its outer end, the pulley being moved by a belt 104, 115 running over a pulley 105, fixed upon shaft 32. The brush 96 is also used to scour the belt 33, and when so used it is forced upward to form contact with the belt by handles 100 and arms 98 and secured by screws 125 102 in slots 101. It may be then driven by a crossed belt 106, which is placed over pulley 103 and pulley 107 on shaft 32 inside of pulley 105, the belt 104 being at such time removed from its pulleys 103 105. The crossed belt 106 causes the brush 96 to revolve in an opposite direction to that of amalgamated belt 33, against which it is forced. Partially covering brush 96 is a shield 108, secured to

arms 98, to prevent water being thrown outward by the brush. Above brush 96 I place a wringing-roller 109, preferably made of rubber and pivotally suspended to arms 110, secured to a shaft 111, journaled to the framework at a point to cause the roller 109 to normally fall away from contact with the belt 33 by its own gravity, the arms 110 extending beyond the framework and terminating in handles 112. By depressing the handles the wringer-roll 109 will be carried against amalgamated belt 33 and effectually remove any water or moisture left on the belt 33 after passing the brush 96.

Upon the forward part of my machine and secured to pieces 9 of the framework are shafts 113, on which are fulcrumed supporting-levers 114, on which are supported rollers 116, made with a yielding surface, such as rubber or other suitable material, the rollers extending across the machine above the amalgamated belt 33 and coming in contact with its upper surface and being revolved thereby and of a length to pass within dams 35. Arms 115 are attached centrally on shafts 113, on which are placed counterweights 117, adapted to be moved on arms 115 to a desired distance to adjust the contact of rollers 116 to belt 33 to any required or requisite pressure. Under belt 33 are other rollers 118, over which belt 33 moves when pressed down by rollers 116. Rollers 118 are secured to shafts 119, journaled in bearings 120, secured to the framework. Front and back of the rollers 116 are placed distributors 121, made of yielding material, reaching across from dam to dam, touching belt 33 at their lower edge and held in position by brackets 122, to which they are secured and which are attached to and above frame members 9.

Having described the means which I have employed to accomplish the results I desire, I will now describe the operation of my mechanism.

The material bearing the fine particles of precious metals having first been subjected to a process exterior to my machine to reduce it to a desired fineness, it is then introduced into the hopper 75 and slides down the inclines 88 89 into the space 87, the slides 85 86 being manipulated to admit a requisite or desirable amount through the space 87 and to the right and left hand screws 78 79, by which it is then carried outward to spouts 83 84 and through which it is conveyed into the disintegrating-cylinder 40. It is then caught by the rods 58, which are revolved by shaft 54 at high velocity, and is thrown against projections 50 of bars 49 and against the rough corners of bars 48, surrounding the inner surface of the disintegrating-cylinder 40, where the particles are disintegrated. They then descend to chutes 72 and are distributed across the amalgamated belt 33 by the directing-ribs 73. The belt 33 will carry the particles outward and under rolls 116, which will press the metallic particles to the amalgamated

surface of the belt 33 and there retain them. As the belt 33 moves by the brush 96 will project water upon the belt-surface 70 and wash away the valueless earthy parts not previously thrown off at the turn of the belt over drum 23, the surplus water being squeezed off by wringer-roll 109. The dams 35 on amalgamated belt 33 prevent any overflow 75 over the sides of the belt. Distributors 121 prevent the massing of the particles on belt 33 in heaps and help to adjust them in an even thin layer to better enable the rolls 116 to press them to the amalgamated surface, 80 the better to enable a more certain securing of their contact with the amalgamated surface, and hence secure a larger recovery of the gold from the sand than could otherwise be had. At any desirable time the machine 85 may be stopped and the amalgamated belt be cleared of its valuable deposit.

Whenever it is desired to scour the amalgamated belt 33 the cross-belt 106 will be applied, 104 being removed, thus causing the 90 brush 96 to revolve in an opposite direction to belt 33, but at a slightly-lessened speed.

Having described the best means I am aware of to accomplish the purpose set forth, I claim—

1. In an amalgamating-machine, a framework adapted to carry horizontal revolving drums at a distance apart and above the same a vertical disintegrating-cylinder, an amalgamated belt upon the drums and means for 100 its driving, revolving and stationary disintegrating means within the vertical cylinder, means to operate the same from the means to run the amalgamated belt, means to introduce material into the disintegrating-cylinder at 105 opposite sides, by feeding mechanism driven from the drum-shaft, and in uniform and in desired quantities, means to deliver the material thereafter to the amalgamated belt, across its width, a plurality of means to press 110 the material to the amalgamated belt as it passes from drum to drum and distributors at each side of the pressing means, substantially as described and set forth.

2. In an amalgamating-machine, a pair of 115 drums, one in fixed position and one in movable position, a belt upon the drums, a cylinder above the belt, a hopper above the cylinder, feeding means within the hopper to deliver material to be operated upon into the cylinder by mechanism worked from the belt-operating mechanism, means within the cylinder to rapidly move and disintegrate the material, means to distribute the material evenly to the belt, multiple rolling means to press the material to the belt, means to distribute the material before and after pressure to the belt, and means from the drum-shaft to drive the mechanism to cleanse the belt, substantially as described.

3. In an amalgamating-machine, a framework, drums thereby supported, one in fixed and one in movable position and means for its moving, multiple rollers upon a belt run

- upon the drums, brackets upon the framework and distributers, composed of continuous flexible material secured to brackets so distributed as to place the distributers at each side of the rollers, in continuous stretch from bracket to bracket, reaching across the belt and adapted to continuously touch the belt upon its upper surface with their lower edge, substantially as described.
10. 4. In an amalgamating-machine, a framework, a fixed and a movable drum thereon, a belt upon the drum, pressure-rollers above and carrier-rollers below the belt, between the drums and pressing upon opposite sides 15 of the belt at the same point, the upper ones being adapted to move to or away from the belt, and means to cause them to press with greater or less degree upon the belt, distributers at either side of the upper rollers, secured to the framework and adapted to touch the belt but to yield under pressure and a flexible dam secured to each outer edge of the belt, substantially as described.
5. In an amalgamating-machine, a framework, drums carried thereby for revolving, 25 one in fixed and one in shifting position, a belt upon the drums, positive means to revolve the drums in unison, a water-receptacle adjacent to the fixed drum, a shaft journaled upon the framework above the receptacle, a revolving brush, yieldingly supported partially immersed in the water, means upon the shaft to support the brush in normal position clear of the belt aforesaid, means upon 30 the arms to elevate the brush to the belt, means to hold it in such elevated position, or remove it from contact with the belt and means from the drum-driving mechanism to revolve the brush, substantially as described.
40. 6. In an amalgamating-machine, a framework therefor, carrying drums and a belt, a water-tank and a brush therein, means to press the brush to the belt or remove it from the belt, and a wringer-roller, suspended from the framework in a manner to cause it to normally fall away from the belt by its own gravity, and means to move the wringer to and 45 press it against the belt or away from contact with the belt, as and for the purposes set forth.
7. In an amalgamating-machine, a framework carrying drums positively driven and a belt thereon, a tank and a brush suspended from the framework to normally be partially 55 immersed therein, means to move the brush upward in the tank to or from the belt, and a shield secured to the elevating means and over the brush to prevent its throwing water outwardly from the belt, substantially as described.
60. 8. In an amalgamating-machine, a framework, drums carried thereon having a belt connection, a disintegrating-cylinder disposed above the belt, a central vertical shaft therein, means to run the drums and the central shaft and rods reaching outward from the central shaft arranged on and secured to the

shaft by clamp-collars having rectangular central holes therein and placed on a shaft of rectangular section, a collar at each side of each rod, a collar fixed on the shaft below the collars and their rods, a nut above the collars and their rods, and thimbles between the pairs of rod-collars, and all clamped in place by the shaft-collar and nut aforesaid in manner set forth and substantially as described. 75

9. In an amalgamating-machine, a framework carrying drums having a belt thereon and a vertical disintegrating-cylinder, a shaft within the cylinder, rods reaching outward 80 therefrom and secured thereto by clamp-collars, means to run the drums and the vertical shaft, segmental rings secured within the cylinder near its upper and somewhat removed from its lower end and rectangular bars secured thereby in a vertical position within the cylinder's inner wall, substantially as described.

10. In an amalgamating-machine, a framework, drums carried thereby, a belt upon the 90 drums, a disintegrating-cylinder disposed above the belt, a shaft within the cylinder, means to move the drums and the shaft, rectangular bars held within the cylinder-walls and secured by segmental rings at their upper 95 and lower ends, and breaker-bars, having inwardly-projecting fingers adapted and spaced to pass between the breaker-bars, substantially as described.

11. In an amalgamating-machine, a framework carrying drums and a disintegrating-cylinder, a belt upon the drums, a shaft within the cylinder and means to move the drums and the shaft, rectangular bars and breaker-bars secured within the cylinder, rods upon 105 the shaft intermeshing with fingers upon the breaker-bars and within the cylinder at its lower end, chutes oppositely disposed and inclined and set apart to form a space between their adjacent edges, and in direction across 110 the belt aforesaid, substantially as described. 100

12. In an amalgamating-machine, a framework carrying drums and a belt thereon, a disintegrating-cylinder and a shaft therein, means to move the drums, the belt, and the 115 shaft, rectangular and breaker-bars secured within the drum, oppositely-inclined chutes located within the cylinder, at its lower part and so disposed as to form a delivery-space between them, and at their lower part, and 120 multiple directing ribs thereon, for the purpose and of the form substantially as described.

13. In an amalgamating-machine, a framework, and thereby held and carried a pair of 125 drums, one in movable, and one in fixed positions on the frames and means to positively revolve the drums by a chain belt connected to a chain-wheel on each drum-shaft and independent of the belt carried thereon supports upon the framework, and therein resting, and thereby carried, a cross-piece, a vertical disintegrating-cylinder supported upon the cross-piece, a step-bearing centrally dis- 130

posed upon the cross-piece, a step therein, a shaft within the step, a shield secured upon the shaft at its upper end projecting downwardly and outwardly over and clear of the 5 step and its bearing, outwardly-projecting bars secured and clamped to the shaft, a bearing at the shaft's upper end secured to the framework and a pulley upon the shaft at its upper end, substantially as described.

10 14. In an amalgamating-machine, drums located upon and supported by the framework of the machine, an amalgamated belt upon the drums, a disintegrating-cylinder upon the framework, a central shaft therein, a hopper 15 above the cylinder, double inclines therein toward the center thereof, and means driven from the drum-shaft aforesaid to gradually remove the material fed to the hopper into spouts leading into the disintegrating-cylinder, substantially as set forth.

20 15. In an amalgamating-machine, a framework supporting drums carrying an amalgam-

ated belt, a disintegrating-cylinder supported by the framework, above the belt and having a shaft therein and means for its driving from the drum-shaft, a hopper above the disintegrating-cylinder, double inclines in the hopper centrally inclined and having a central space between them, oppositely-disposed slides under the inclines to increase or decrease the central space, a shaft within the hopper, right and left hand screw-blades thereon, spouts from the hopper-bottom at the end of the screws and leading into the disintegrating-cylinder, and means to positively move the shaft and screw-blades, from the drum-shaft of the machine, substantially as set forth. 25 30 35

In testimony whereof I affix my signature in presence of two witnesses.

ANDREW M. ERNSBERGER.
